UNITED STATES PATENT OFFICE.

JAMES S. BROWN, OF PAWTUCKET, ASSIGNOR TO JOSEPH R. BROWN AND LUCIAN SHARPE, OF PROVIDENCE, RHODE ISLAND.

IMPROVEMENT IN FRICTION-CLUTCHES.

Specification forming part of Letters Patent No. 42,525, dated April 26, 1864.

To all whom it may concern:

Be it known that I, JAMES S. BROWN, of Pawtucket, in the county of Providence and State of Rhode Island, have invented a new and useful improvement in the friction-clutch for connecting and disconnecting a loose pulley with or from its shaft or axle and for other purposes; and I do hereby declare that the following is a full, clear, and exact description of the same, reference being had to the accompanying drawings, making part of this specification, in which—

Figure 1 is a transverse section of my improved friction-clutch and pulley, arranged in proper form on a shaft, B. Fig. 2 is a view of the interior face of the segment-plate D, Fig. 1, showing one of the segments E within its slide and the spring-connections S S. Fig. 3 is an end view of the said segment-plate D. Figs. 4 and 5 are two views of the said segments E, detached. Figs. 6 and 7 are two views of the levers G G, Fig. 1.

Similar letters of reference indicate corresponding parts in all the figures.

My improvement consists in a peculiar arrangement of the levers and segments of a friction-clutch, whereby the construction is greatly simplified and rendered more substantial, and a more direct and forcible pressure against the friction-surface, and consequently a greater clutching force, is obtained than is attainable by the differently-arranged friction-clutches heretofore known and used.

To enable others skilled in the art to make and use my invention, I will proceed to describe the same.

In the accompanying drawings, B is a shaft and P is a pulley thereon, having a suitable length of hub to give it steadiness upon the shaft, and having the rim P' formed almost wholly upon one side of the plate or arms m, the interior circular surface of which (rim) is turned to a smooth bearing for the clutching device, which consists of two segments, E E, of form as shown in Figs. 1, 2, and 4, sliding freely in the guides C C, formed in the segment-plate D, Figs. 2 and 3, by means of two straight levers, G G, Figs. 1, 6, and 7, swinging upon two fulcrum-pins, d d, in the lugs g g of the segment-plate, and passing through and exerting their force against the edge of the openings l l, in sliding plates of the seg-

ments E E, at a point on the levers near the fulcrum-pins, by motion and power applied to the opposite ends of the said levers through the medium of the sliding wedge-collar F upon the shaft. The said segments E are connected by means of two spiral springs, s s, attached to hooks t t upon each side thereof, as shown in Fig. 2, in order to draw each segment toward the center and from contact with the inner surface of the wheel-rim at the proper time. A set-screw, i i, is inserted in the long arm of the levers G to adjust and regulate the sliding movement of the two segments and their consequent pressure against the friction-surface on the wheel-rim, the wedge collar operating against the heads of such set-screws.

The pulley F, as represented, is intended to turn freely on the shaft B and is held in its position under such circumstances by the fixed collar r on one side and the segment-plate D made fast to the shaft by the set-screw h, through its hub, as seen in Fig. 3, upon the other side, whereby the parts composing the clutch are secured to and revolve with the shaft.

The wedge collar F is formed with two wedges or conical ends to operate a friction-clutch upon both sides and with a deep score, j, in the middle for the reception of the forked shipper, which is generally used to slide it either way upon the shaft.

When the cone or circular wedge is slid between the set-screws i i in the ends of the levers G the segments E are pressed from the center directly against the under side of the wheel-rim, and when the said cone or wedge is slid from between the said set-screws the reaction of the springs s s withdraws the segments from contact with the rim of the wheel, the former connecting the pulley with the shaft, and the latter disconnecting the pulley from the shaft and permitting each to move independently of the other.

It will be seen that very little labor is involved in the construction of this clutch and that every part of the work may be readily fitted up with the commonest tools by any ordinary machinist.

It will also be seen that the segments have a direct action and pressure at right angles with the shaft against the under surface of the wheel-rim, whereby any wear upon the

friction-surface of said segments is calculated to fit the same more closely and perfectly to the surface of the wheel-rim, and thus to insure a more perfect and forcible clutching action than can possibly be attained by an oblique or other movement of the said segments that is less direct; and it will be seen that the arrangement of the levers G with the segments is such that a sufficient sliding movement is imparted to the said segments from a point on the lever at about a quarter of the distance of its length from the fulcrum-pin d, so that the power exerted upon the long arm of the lever through the medium of the wedge-collar F is multiplied threefold when thus transmitted to the segment, which, as a result, is obviously very desirable and useful, and it is this multiplication of the power, combined with the direct action and pressure of the said segments, which chiefly distinguishes my invention from other arrangements which have been heretofore employed for this purpose.

I am aware that similar segments, connected by toggles with a sliding sleeve and surrounded or encompassed by an endless spiral spring to withdraw the segments from contact with the wheel-rim, have been previously patented by Wendell Wright, June 15, 1852, and I would not, therefore, be understood as claiming the segments when so arranged.

I am aware also that a similar wedge-collar for operating two levers or clamps to clutch the V-edge of a disk or collar has been previously patented by Francis A. Pratt, September 4, 1860, and I would not, therefore, be understood as claiming such wedge-collar or the arrangement of parts therein set forth.

I am aware, too, that the said wedge-collar, in combination with two angular levers, the action of which is adapted to the rim of the pulley, has been previously patented by the said Francis A. Pratt, November 26, 1861, and I would not, therefore, be understood as claiming such combination, as neither this or the other arrangements of the said Pratt and Wright, above referred to, are capable of producing the desirable results herein described as peculiar to my improved arrangement.

Having thus described my invention, what I claim, and desire to secure by Letters Patent, is—

The combination and arrangement of the segments E E, the segment-plate D, and levers G G, with the wedge-collar F and pulley P, substantially as described, for the purpose specified.

JAMES S. BROWN.
